[57] CLAIM

The ornamental design for a tape measure, as shown and described.

DESCRIPTION

FIG. 1 is a perspective view of a tape measure showing a first embodiment of our new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is bottom plan view thereof;

FIG. 7 is a top plan view thereof;

FIG. 8 is a perspective view of a tape measure showing a second embodiment of our new design;

FIG. 9 is a left side elevational view thereof;

FIG. 10 is a right side elevational view thereof;

FIG. 11 is a front elevational view thereof;

FIG. 12 is a rear elevational view;

FIG. 13 is a bottom plan view thereof; and,

FIG. 14 is a top plan view thereof.

The broken line showing is for illustrative purposes only and forms no part of the claimed design.
